(57) **CLAIM**

The ornamental design for a carrying and display tray, as shown and described.

DESCRIPTION

FIG. 1 is a top perspective view of the carrying and display tray of the invention showing our new design;

FIG. 2 is a front elevational view thereof, the back view being a mirror image thereof;

FIG. 3 is a side elevational view thereof, the opposite side being a mirror image thereof;

FIG. 4 is a top plan view thereof;

FIG. 5 is a bottom plan view thereof;

FIG. 6 is a top view showing another embodiment of the carrying and display tray of our invention and showing our new design having a slatted bottom;

FIG. 7 is a bottom view thereof, the side and front views being the same as FIGS. 2 and 3;

FIG. 8 is a perspective view showing another embodiment of the carrying and display tray of our invention and showing our new design;

FIG. 9 is a front elevational view thereof, the back view being a mirror image thereof;

FIG. 10 is a side elevational view thereof, the opposite side being a mirror image thereof;

FIG. 11 is a top plan view thereof, the bottom plan view being a mirror image thereof; and,

FIG. 12 is a top view showing another embodiment of the carrying and display tray of our invention and showing our new design having a slatted bottom, the bottom view being a mirror image thereof, and the side and front views being the same as FIGS. 9 and 10.
